UNITED STATES PATENT OFFICE.

FREDERIC E. BALDWIN, OF NEW YORK, N. Y.

DESIGN FOR A LAMP-BODY FOR MINERS' LAMPS.

45,514.

Specification for Design.

Patented Mar. 31, 1914.

Application filed September 18, 1913. Serial No. 790,562. Term of patent 14 years.

To all whom it may concern:

Be it known that I, FREDERIC E. BALDWIN, a citizen of the United States, residing at New York city, in the borough of Richmond and State of New York, have invented a new, original, and ornamental Design for Lamp-Bodies for Miners' Lamps, of which the following is a specification, reference being had to the accompanying drawing, forming part thereof.

The drawing is a side elevation of a lamp body embodying my design.

I claim:

The ornamental design for a lamp-body for a miner's lamp, as shown.

In testimony whereof, I have hereunto set my hand, in the presence of two subscribing witnesses.

FREDERIC E. BALDWIN.

Witnesses:

A. WHITE,
P. N. TILDEN.
